Benjamin G. Edelman, Brooklyn, N.Y., assignor to
United Metal Goods Mfg. Co., Inc., Brooklyn, N.Y.,
a corporation of New York

Filed Oct. 12, 1959, Ser. No. 57,881

Term of patent 14 years

(Cl. D67—4)

FIG. 1

FIG. 2

FIG. 1 is a perspective view of the ice container, showing my new design. The side not shown is substantially the same as the side shown.

FIG. 2 is a fragmentary rear perspective view thereof.

The dominant features of my design reside in the portions shown in full lines.

I claim:

The ornamental design for an ice container for household use, as shown and described.
